J. P. RUFFENO.
AUTOMATIC MONKEY WRENCH,
APPLICATION FILED MAY 29, 1917.

Patented Mar. 5, 1918.

UNITED STATES PATENT OFFICE.

JOSEPH P. RUFFENO, OF OPELOUSAS, LOUISIANA.

AUTOMATIC MONKEY-WRENCH.

1,258,361.

Specification of Letters Patent.

Patented Mar. 5, 1918.

Application filed May 29, 1917. Serial No. 171,703.

To all whom it may concern:

Be it known that I, JOSEPH P. RUFFENO, a citizen of the United States, residing at Opelousas, in the parish of St. Landry and State of Louisiana, have invented certain new and useful Improvements in Automatic Monkey-Wrenches, of which the following is a specification, reference being had thereto in to the accompanying drawing.

10 This invention relates to an automatic monkey wrench and has for its object the production of a simple and efficient device which is provided with an adjustable jaw and which may be clearly and conveniently moved to a desired set position.

15 Another object of this invention is the production of a simple and efficient means for holding the adjustable jaw in a set position.

20 With these and other objects in view, this invention consists of certain novel constructions, combinations and arrangements of parts as will be hereinafter more fully described and claimed.

25 In the drawings:

Figure 1 is a side elevation of the wrench. Fig. 2 is a central vertical section thereof.

Fig. 3 is a rear elevation of a portion of the shank of the wrench.

30 Fig. 4 is a section taken on line 4—4 of Fig. 1.

Fig. 5 is a section taken on line 5—5 of Fig. 1.

35 Fig. 6 is a detail perspective of the latch used in connection with the present invention.

Fig. 7 is an end view of the latch shown in Fig. 6 in an operative position.

40 Fig. 8 is a detail perspective view of a modified form of the latch which may be used in connection with the present invention.

45 By referring to the drawings it will be seen that 1 designates the handle or shank of the wrench which is provided with a stationary jaw 2 which jaw 2 is provided with a plurality of gripping teeth 3 formed upon the face thereof, which gripping teeth are cut to converge toward each other near the center of the jaw as illustrated clearly in Fig. 4 of the drawings. A stationary shank 4 is secured to the jaw 2 and comprises an

elongated body having a jaw head 5 formed upon the top thereof as clearly shown in Figs. 1 and 2 of the drawings. This shank 4 is 55 provided with a notch 5 formed in the rear face thereof, within which notch 5 fits a reduced web or binding strap 7. This binding strap 7 is riveted or otherwise secured to the sides of the jaw 2 as illustrated in Fig. 60 1 of the drawings and it will be seen that the strap 7 will constitute an efficient guide for the depending fingers 8 of the adjustable jaw 9. It should be understood that the shank portion 4 is formed integral with the 65 jaw 2 as shown in Fig. 2 of the drawings. The adjustable jaw 9 also carries a guide plate 10 which is secured to the front edges of the fingers as shown in Figs. 1 and 2 of the drawings and it will, therefore, be seen 70 that an efficient guide is provided for providing a wide bearing space for the shank 4 while passing through the adjustable jaw 9. A ratchet bar 11 is secured to the rear of the adjustable jaw 9 by fitting in the bifurcated end 12 thereof as shown in Fig. 2 of the drawings. This ratchet bar 11 extends 75 down through a socket 13 formed in the handle 1 and is engaged by the lower end thereof by means of an expansion spring 14, 80 which spring 14 is seated in a socket 15 formed in the handle 1. A removable plate 16 is secured to the handle 1 at the lower end thereof and is adapted to close the lower end of the socket 15 within which the spring 14 is mounted. It will, therefore, be seen 85 that this plate 16 may be removed for the purpose of obtaining access to the socket 15. The plate 16 is provided with a beveled rear edge 17 which fits against the beveled edge 90 18 of the handle 1.

A latch 19 extends through the jaw 2 and this latch 19 carries a spring 22 which is secured at one end to the plate 20 which is secured to the jaw 2 and at the other end 95 to the latch 19 in order to at all times yieldably hold the latch 19 in engagement with the ratchet teeth 21 formed upon the ratchet bar 11. The latch 19 passes through a plate 20 formed upon the edge 2 as illustrated in 100 Fig. 2 of the drawings.

The latch 19 is provided with a rearwardly extending end 23 which is then folded to extend forwardly for providing a for-

wardly extending finger 24, which forwardly extending finger 24 terminates in a tooth engaging lip 25. The tooth engaging lip 25 engages the ratchet teeth 21 upon the ratchet bar 11 for holding the adjustable jaw 9 in a set position. It of course should be understood that the adjustable jaw 9 is provided with suitable gripping teeth 26 upon the under face thereof for coöperating with the gripping teeth 3 formed upon the adjustable jaw 2.

As shown in Figs. 4 and 8 of the drawings, a modified form of a latch 27 is illustrated which comprises an elongated bar having an operating knob 28 formed at one end. A tooth engaging lip 29 is carried by the opposite end of the latch 27 and is provided with a rearwardly extending thumb engaging tongue 30, which is adapted to be engaged by the operator for moving the tooth engaging lip 29 out of engagement with the ratchet teeth 21 carried by the ratchet bar 11. It should be understood that the structure as shown in Figs. 6 and 7 may also be thrown out of engagement with the ratchet teeth 21 by means of the thumb of the operator engaging the rearwardly extending portions 23 and 24 of the latch 19.

From the foregoing description, it will be seen that a very simple and efficient device has been provided for efficiently adjusting a wrench so that the desired sized nut or other object may be gripped thereby, whereby it should be understood that the object may be either gripped between the jaws 2 and 9 or between the jaws 9 and 5.

What is claimed is:—

1. A monkey wrench of the class described comprising a handle, a stationary jaw integrally formed upon said handle, a stationary shank integrally secured to said stationary jaw and projecting above said stationary jaw, a jaw head secured to the upper end of said shank, an adjustable jaw slidably mounted upon said shank, said adjustable jaw provided with a plurality of fingers engaging and sliding upon the side of said shank, a strap secured to said shank and also secured to the sides of said stationary jaw and constituting a guiding loop, said depending fingers of said adjustable jaw extending therethrough, a ratchet bar secured to the rear end of said adjustable jaw, means engaging said ratchet bar for holding the same in set position, and yieldable means positioned within said handle for normally urging said adjustable jaw to a closed position with respect to said jaw head.

2. A monkey wrench of the class described comprising a handle, a stationary jaw integrally formed upon said handle, a stationary shank integrally secured to said stationary jaw and projecting above said stationary jaw, a jaw head secured to the upper end of

said shank, an adjustable jaw slidably mounted upon said shank, said adjustable jaw provided with a plurality of fingers engaging and sliding upon the side of said shank, a strap secured to said shank and also secured to the sides of said stationary jaw and constituting a guiding loop, said depending fingers of said adjustable jaw extending therethrough, a ratchet bar secured to the rear end of said adjustable jaw, means engaging said ratchet bar for holding the same in set position, yieldable means positioned within said handle for normally urging said adjustable jaw to a closed position with respect to said jaw head, a latch carried by said stationary jaw, a spring carried by said latch, means for facilitating the throwing of said latch to an inoperative position, and said latch provided with a tooth engaging end for engaging the teeth of said ratchet bar for holding said adjustable jaw in set position.

3. A monkey wrench of the class described comprising a handle, a stationary jaw integrally formed upon said handle, a stationary shank integrally secured to said stationary jaw and projecting above said stationary jaw, a jaw head secured to the upper end of said shank, an adjustable jaw slidably mounted upon said shank, said adjustable jaw provided with a plurality of fingers engaging and sliding upon the side of said shank, a strap secured to said shank and also secured to the sides of said stationary jaw and constituting a guiding loop, said depending fingers of said adjustable jaw extending therethrough, a ratchet bar secured to the rear end of said adjustable jaw, means engaging said ratchet bar for holding the same in set position, yieldable means positioned within said handle for normally urging said adjustable jaw to a closed position with respect to said jaw head, said stationary jaw provided with an aperture formed therein, a latch mounted therein, a spring carried by said latch and secured at one end to said jaw and at the other end to said latch, and said latch provided with a rearwardly extending portion terminating in a forwardly extending portion, said forwardly extending portion being placed above said rearwardly extending portion and terminating in a tooth engaging tongue for engaging the teeth of said ratchet bar, said forwardly and rearwardly extending portions of said latch being adapted to facilitate the throwing of said tooth engaging tongue out of engagement with the teeth of said ratchet bar.

4. A wrench of the class described comprising a handle, a stationary jaw, a shank integrally secured to said stationary jaw, a jaw head carried by said shank, said shank provided with a transversely extending notch upon the rear face thereof, a metallic

strap secured to the side of said stationary jaw and provided with a reduced web portion fitting in said notch, an adjustable jaw, means for holding said adjustable jaw in a set position, said adjustable jaw provided with depending side fingers working through said notch and strap, a guide plate secured to the front faces of said fingers and com-

prising a wide bearing portion for holding said adjustable jaw upon said shank, means 10 for holding said adjustable jaw in a set position while said wrench is in operation.

In testimony whereof I hereunto affix my signature.

JOSEPH P. RUFFENO.
